WINDOW CLEANING DEVICE

Filed Dec. 29, 1922

INVENTOR.
GOTTLIEB BACKHAUS
BY
Richard D. Dow
ATTORNEY.

UNITED STATES PATENT OFFICE.

GOTTLIEB BACKHAUS, OF NEW YORK, N. Y.

WINDOW-CLEANING DEVICE.

Application filed December 29, 1922. Serial No. 609,714.

To all whom it may concern:

Be it known that I, GOTTLIEB BACKHAUS, a citizen of the Republic of Germany, residing at New York city, in the county of New York and State of New York, have invented certain new and useful Improvements in Window-Cleaning Devices, of which the following is a specification.

This invention relates to window cleaning devices and more particularly to a novel and improved mechanism wherein the outside surface of the upper and lower sections of a window may be cleaned from a position on the inside of the window sash with facility and ease and avoiding the danger incident to this character of work.

The primary object of my invention is the construction of a manually operable window cleaning device constructed and arranged so that access can be had to the outer surface of the windows to be cleaned including provision for actuating the cleaning or wiping element from a position on the inside of the window sash.

A further object of my invention is the construction of an outside window cleaning mechanism including the vertically operable rack on which the cleaning device or wiper is mounted and provision for actuating the latter from a position on the side of the window sash by suitable gearing constructed and arranged so as to impart a reciprocatory motion to the cleaning or wiping element.

I accomplish the above objects and others which will be more readily understood when considered in connection with the accompanying drawings showing a preferred embodiment of my invention and wherein:

Figure 1 is a view showing the application of my invention in connection with a conventional type of window sash.

Figure 2 is an enlarged view partly in section showing the arrangement of the gearing and the actuating mechanism for the cleaning or wiping element.

Figure 3 is a cross section through the gearing housing.

Referring now to the drawings wherein like reference characters designate corresponding parts throughout the several views, 5 designates the window casing and 6, 7, the window sashes, the pane of glass carried thereby being indicated at 8.

The device proper consists of a gearing housing 9 in which a horizontal shaft 10 is mounted in suitable bearings 11. A large

toothed gear 12 mounted on the shaft 10 is adapted to engage a vertical rack bar 13, having rack teeth 14 thereon, which rack bar extends through a vertical recess in the outer end 15 of the housing as clearly shown by Figure 2 of the drawings. The extreme upper end of the rack bar is provided with a transverse slot which receives a sleeve 16, said sleeve supporting a cleaner or wiper carrying bar or rod 17 in adjusted position by the thumb screw 18, the outer end of said rod or bar 17, supporting the wiper or cleaner 19 which work up and down over the windows to be cleaned.

Secured to the front wall of the housing 9, I have provided a bushing 20, to which the tube 21 is threadedly connected and in which the operating mechanism is found. A block 22 secured within the tubing 21 supports the spindle 23 of a worm shaft 24, the latter extending through the front wall of the housing 9. The opposite end of the shaft 24 supports and carries a bevelled gear 25 which meshes with the gear 26, mounted on the shaft 10, whereby when motion is imparted to the shaft 24, the gears 25 and 26 will actuate the meshed tooth gear 12 and the rack bar 13 as is well understood. The shaft 24 above referred to is provided with a groove 27 and on the shaft, I have provided a feed block 28 co-operating with the shaft in such manner that when the block 28 is actuated, rotation will be imparted to the shaft 24 and consequently to the gearing. The block 28 is preferably provided with a stud which rides in the groove 27 and connected thereto, I have provided a pair of parallel rods 30, 29, which are secured at their opposite ends to the head 31 of an interfitting, sliding plunger 33, on which the handle 34 is supported, whereby the device can be actuated manually.

From the above construction, it will be readily seen that as the handle 34 is gripped and moved inwardly and outwardly, the rods 29, 30 which carry the member 28, will cause the latter to move backward and forward, thus causing rotation of the worm shaft 24, whereupon rotary motion is imparted to the bevelled gears 25, 26 and consequently actuate the rack bar 13 as heretofore explained. Of course the tube 21 is held in one hand when the handle 34 is actuated to steady the device and consequently permit of the movement of the hous-

ing 9 across the window sill during the cleaning or wiping of the window.

While I have illustrated and described my invention with some degree of particularity, I realize that in practice various alterations therein may be made. I therefore reserve the right and privilege of changing the form of the details of construction or otherwise altering the arrangement of the correlated parts without departing from the spirit of the invention or the scope of the appended claims.

Having thus described my invention, what I claim as new and desire to secure by United States Letters Patent is:—

1. A window cleaner comprising a support, a vertically operable rack bar slidable through the support, a wiper carried at one end of the rack bar, meshed gearing mounted within the support and cooperating with the rack bar, a worm shaft and manually operable means reciprocable on said shaft for operating said worm shaft to impart reciprocatory motion to the rack bar.

2. A window cleaner comprising a support, a vertically operable rack bar slidable through a recess in the rear of the support, gearing mounted within the support and meshing with the rack bar, a tubular ex-

tension housing on said support and extending at right angles thereto, a worm shaft mounted within the housing, a bevel gear carried by said worm shaft meshing with the first mentioned gearing and manually operable means reciprocable on said worm shaft for actuating said shaft to impart reciprocatory motion to the rack bar.

3. A window cleaner comprising a support, a vertically operable rack bar slidable through a recess in the rear of the support, a horizontal shaft and a toothed gear mounted on the shaft in meshing relation with the rack bar, an exterior housing connected to the support, a worm shaft within the housing, a bevel gear mounted at the inner end of the worm shaft, a gear carried by the horizontal shaft and meshing with the last mentioned bevel gear, a feed nut cooperating with the worm shaft, and manual means for actuating said feed nut to impart reciprocatory motion to the gearing and the rack bar.

In testimony whereof I affix my signature in presence of two witnesses.

GOTTLIEB BACKHAUS. [L. S.]
